EUGENE A. KUEN, OF CINCINNATI, OHIO, AND CLARENCE L. PATTERSON, OF DETROIT, MICHIGAN.

RADIOFREQUENCY TRANSFORMER AND CIRCUITS THEREFOR.

Application filed January 26, 1925. Serial No. 4,715.

This invention relates to a radio frequency transformer and circuit therefor which have been devised to produce a radio receiver of unusual merits, in which:

5 An object has been to produce a receiver which is unusually quiet and highly selective in its operation, and in which:

10 A further object is to produce a receiver which possesses characteristics rendering it quite sensitive to the reception of distant signal energy and of pleasing tone and volume.

15 These and other objects are attained in the transformer and circuit described in the following specification and illustrated in the accompanying drawing, in which:

20 Fig. 1 is a somewhat diagrammatic view illustrative of our improved transformer and circuit therefor, as used in connection with radio tubes of the construction employing two grid elements.

Fig. 2 is a view similar to Fig. 1, but showing a modified form of transformer embodying the principles of our invention, in connection with a circuit employing tubes having two grid elements, as in the circuit shown in Fig. 1.

25 Fig. 3 is a fragmental diagrammatic view showing the transformer employed in the circuit shown in Fig. 1, adapted to the usual three element or single grid tube.

30 Fig. 4 is a view similar to Fig. 3, but showing the transformer employed in the circuit shown in Fig. 2, adapted to the usual three element or single grid tube.

35 We will first describe the transformers we have devised and will then describe the circuits in which they play such an important part. The first transformer construction to be described is that shown in Figs. 1 and 3.

40 This transformer, which is of the radio frequency type, employs three windings, one of which is the usual primary which we have designated by the reference letter P, the other two windings being in the form of 45 two separate secondaries which we have designated by the reference letters S' and S''. The actual arrangement of the primary and secondary coils may conveniently and preferably be such that the convolutions of the 50 three coils lie concentrically with relation to each other, with one secondary located on each side of the primary winding. Inasmuch as each coil has its own terminals

there will be a total of six terminals for each of our improved transformers as shown at 55 1, 1, 1 and 2, 2, 2 in Fig. 1. However, because of the fact that the terminals 1, 1 of the secondary coils S', S'' are, in the preferred circuit embodying our improved transformer, connected, as shown in Fig. 1, 60 the number of terminals may readily be reduced to five if desired. The proportion of the windings in this form of our improved transformer is preferably such that the two secondaries are identical as to the number of 65 turns and size of wire.

In the transformer shown in Figs. 2 and 4 the actual number of windings is but two, consisting of a primary P and a secondary S, but the secondary is tapped at its exact center as shown at 3, so that the secondary is divided into two equal windings which produce in effect two secondaries. However, inasmuch as the secondary still has its two usual terminals 1 and 2, and the primary 70 has its usual terminals 1 and 2, the transformer as a whole has five terminals which afford connection with one primary and two secondary windings as in the previously described transformer construction, if we consider the connection of the two terminals S' and S'' of the secondaries as one terminal after they are connected.

75 In the connection of our improved transformer which embodies the form shown in Fig. 1, the circuit, as shown in this view, contemplates the use of a radio tube having two grid elements G' and G''. The terminal S'' is connected directly to the grid G' while the terminal S'' is connected to grid 80 G preferably through an interposed fixed condenser C. The terminal P is connected with the plate of the preceding input tube with which the usual antenna and ground circuit connections are made, such other circuit details being merely generally designated by the terminal posts marked "Input". In the drawing we have shown two steps of 85 radio frequency amplification through the use of our improved transformer, although as many may be employed as desired. From the radio frequency stages thus illustrated, the usual radio frequency transformer T is used for the detector connection in the conventional manner as shown. A three element or single grid tube has been shown for 90 95 100 105 110

detector use. In the circuit a potentiometer or voltage divider may be employed and a rheostat R may be inserted to control the tube filament illumination. The output of the circuit is from the terminals so designated, and the battery connections are made as indicated at the proper terminal posts.

In order to use the usual three element or single grid tube our improved double secondary transformer may be connected somewhat as shown in Fig. 3. In this connection the primary winding terminals are connected as has been previously described, and the secondary terminals S'^1 and S''^1 are connected in the same manner. However, the terminals S'^2 and S''^2 are connected by bringing them both together into the single grid G connection with the condenser C preferably interposed between the juncture of the terminal P'^2 and S''^2 of the secondary coil S'' , so that only the secondary S'' is affected by the condenser.

In the use of a single grid tube for the circuit using the transformer embodying the form shown in Fig. 2, the terminals S^2 and S^3 , as shown in Fig. 4, are connected together into the single grid G with the condenser C located between the juncture of the terminals S^2 and S^3 so that only the portion of the secondary between terminals S^1 and S^3 , which is affected by the tap taken off at terminal S^3 , will be controlled preferably by condenser C .

The use of a double grid tube in connection with the transformer shown in Figs. 2 and 4, is clearly shown in Fig. 2. The terminal S^2 is connected with one grid G' while the terminal S^3 is connected with the other grid G'' preferably through the condenser C as shown. All other features of the circuit are identical with that shown in Fig. 1 and need not be specifically described other than to point out that there is but one secondary terminal 1 one each transformer to be connected to the "input" and voltage divider V , instead of two as in Fig. 1.

The functioning of our improved transformer and circuit may be quite obvious to those skilled in the art, but it may be well to set forth briefly the general principle of operation involved. By subjecting each of the secondary windings to identically the same input and potentiometer controlled voltage conditions through duplicate connections at terminals S'^1 and S''^1 in the form of the transformer shown in Fig. 1, these coils will respond in the same manner. However, the action of coil S'' will be held back somewhat and allowed to issue in a more smooth manner by the action of condenser C so that the objectionable impulses of energy received from the antenna circuit will be ironed out as it were. One secondary will operate to allow these impulses to pass freely while the other, due

to its condenser connection, will operate to hold the impulses in a slightly retarded condition and allow them to issue with less blast than the other, much as the muffler of an internal combustion engine allows complete exhaustion to take place, but overcomes the objectionable noise of explosion. This effect also assists the functioning of secondary S' by bringing about a stepping of the energy impulses slightly out of phase through the retarding action of one tube over the other, thus, in a measure producing a neutralization which has noticeably beneficial results in the clearness, tone and volume of the signal reception.

Not only is signal reception very materially improved in this manner, but the reception of such disturbing influences as static discharges, local interference through re-radiating receivers, leakage of power transformers, sparking commutators and similar annoying sources of trouble of this nature, is substantially eliminated.

The transformer shown in Figs. 2 and 4 operates in identically the same manner because its central secondary winding tap produces in effect two secondary coils which function identically, one of which however, may be controlled in a measure by the condenser C as has been explained above.

Having thus described our invention what we claim is:

1. In a wave signal responsive circuit, a radio tube, a transformer containing a primary winding and two secondary windings, said primary winding having connection at one terminal to the plate of the tube and at its opposite end to a source of plate potential, said secondary windings connected together at one terminal and to the filament circuit of the tube at their joined terminals, the opposite terminals of the secondary windings having connection with the grid circuit of the tube, one of said opposite secondary terminals having a condenser interposed in its connection with the grid circuit.

2. In a wave signal responsive circuit, a radio tube having two grids, a transformer containing a primary winding and two secondary windings, said primary winding having connection with the plate circuit of the tube, one of the secondary windings having direct connection with one of the grids of the tube, and a condenser connected with the other secondary winding and the second grid of the tube.

3. In a wave signal responsive circuit, a radio tube having two grids, a transformer consisting of a primary winding and two secondary windings which are duplicates of each other and are wound concentrically relatively to one another, said primary winding having connection with the plate circuit of the tube, one of said secondary windings

having connection with the circuit of one of the grids of the tube, and a condenser connected with the terminal of the other secondary corresponding to the terminal of the

5 first mentioned secondary connected with the first mentioned grid, said condenser having connection with and connecting the grid

terminal of the second mentioned secondary to the other grid of the tube.

In testimony whereof we have hereunto 10 affixed our signatures.
